UNITED STATES PATENT OFFICE.

JOHN C. BROWN, OF ATLANTA, GEORGIA.

COMBINED SQUARE AND BEVEL FOR ASCERTAINING THE LENGTH OF RAFTERS, &c.

1,243,678.

Specification of Letters Patent. Patented Oct. 16, 1917.

Application filed August 9, 1916. Serial No. 113,986.

To all whom it may concern:

Be it known that I, JOHN C. BROWN, a citizen of the United States, residing at Atlanta, in the county of Fulton and State 5 of Georgia, have invented certain new and useful Improvements in Combined Squares and Bevels for Ascertaining the Length of Rafters, &c.; and I do hereby declare the following to be a full, clear, and exact description of the invention, such as will enable others skilled in the art to which it appertains to make and use the same.

The invention relates to a combined square and bevel for ascertaining the length 15 of rafters, etc.

The object of the present invention is to provide a simple, practical and comparatively inexpensive combined square and bevel equipped with pivoted blades arranged 20 for use in connection with the hip and common rafters of a roof for enabling the roof dimensions as to the bevel or inclination of the common and hip rafters and the length of the same to be readily ascertained.

25 A further object of the invention is to provide a device of this character provided with means for connecting the pivoted rafter blades for effecting an automatic adjustment of one of the blades when the other is manually adjusted so that the measuring instrument will indicate the bevel of both the common and hip rafters of a roof.

The invention also has for its object to provide means for enabling the pivoted 35 rafter blades to be readily adjusted on a square and securely clamped in their relative adjustments.

With these and other objects in view, the invention consists in the construction and 40 novel combination of parts hereinafter fully described, illustrated in the accompanying drawings, and pointed out in the claims hereto appended; it being understood that various changes in the form, proportion, 45 size and minor details of construction, within the scope of the claims, may be resorted to without departing from the spirit or sacrificing any of the advantages of the invention.

50 In the drawing.

Figure 1 is a side elevation of a combined bevel and square constructed in accordance with this invention,

Fig. 2 is a plan view,

Fig. 3 is a vertical sectional view on the 55 line 3—3 of Fig. 1.

Fig. 4 is a longitudinal sectional view illustrating the means for connecting the pivoted blades for securing a simultaneous movement of the same when one of the 60 parts is adjusted,

Figs. 5 and 6 are detail views of the pivoted ends of the hip and common rafter blades,

Fig. 7 is a detail view illustrating the construction of the front rear and intermediate sections of the combined clamp and handle.

Fig. 8 is a bottom plan view of the combined handle and clamp.

Like numerals of reference designate corresponding parts in the several figures of the drawings.

In the accompanying drawings in which is illustrated the preferred embodiment of the invention, the measuring instrument 75 comprises in its construction a metallic square 1, pivoted blades 2 and 3 and a combined handle and clamp 4 constituting a stock and composed of front, rear and intermediate sections 5, 6, and 7 which receive the blades 2 and 3 between them and pivotally connect and clamp the said blades in their adjustment. The combined handle and clamp 4 which may be constructed of any suitable material is adapted to be fitted 80 against the arm 8 of the square 1 at the outer edge thereof, as clearly illustrated in Fig. 1 of the accompanying drawings and the rear section is provided with projections or flanges 9 forming a guide and adapt 90 to fit against the face of the square to enable the rear section of the combined handle and clamp to be accurately positioned against and in parallelism with the arm of the square. The sections are connected at 95 their lower ends by hinges and the upper portions of the sections are recessed at their inner faces to provide intervening spaces 12 and 13 for the reception of the rafter blades. The common rafter blade which is 100 arranged between the front and intermediate sections of the combined clamp and handle is provided at its upper portion with an arcuate groove 14 formed by stamping the blade and providing a projecting rib 105 at the opposite face of the blade 2. The other or hip rafter blade 3 is provided with a similar arcuate groove 15 formed in the

opposite face of the blade 3 by stamping the same. The inner or intermediate section 7 of the combined clamp and handle is provided at its upper portion with ar-
5 cuate ribs 16 arranged concentric with the grooves 14 and 15 and projecting into the same to form a guide for the blades 2 and 3 in the pivotal movement thereof. The guide ribs 16 and the curved grooves are described on an arc having as its center a point on the graduated outer edge of the arm 8 of the square. By this construction the blades 2 and 3 are mounted for pivotal movement on the handle or clamp on a com-
10 mon axis. The blades are clamped in their adjustment by means of a screw 17 pro-
15 vided at the front with a head and extending loosely through the sections 5 and 7 and threaded into an opening 18 in the rear section 6. The openings 19 and 20 in the sections 5 and 7 are smooth, and the said sections 5, 6, and 7 of the combined handle and clamp are forced into engagement with the blades 2 and 3 which are securely
20 clamped in their adjusted positions. When the screw is loosened the blades are adapted to be adjusted with relation to each other and to the body and arm of the square.

The blades are caused to move simultane-
30 ously when one of them is adjusted by means of a connecting lever 21 extending longitudinally of the said blades and pivoted at an intermediate point by a screw 22 or other suitable fastening device to the front section 5 of the combined handle and clamp and having its inner and outer arms connected respectively with the blades 2 and 3. The blade 2 is provided at the inner side of the pivot 22 with a longitudinal slot
35 40 23 which receives a suitable pivot 24 that is carried by the inner arm of the lever 21. The blade 2 terminates at its upper end adjacent to the combined clamp and handle while the other blade 3 is extended out-
45 wardly beyond the same and is provided in its outer portion with a longitudinal slot 25 in which operates a pivot 26, of the outer arm of the lever 21. The pivots 24 and 26 which are provided at their inner ends with
50 heads carrying spacing sleeves 27 and 28 which are interposed between the connect-
55 ing lever and the blades 2 and 3 and the front or outer ends of the said pivots 24 and 26 are threaded for the reception of nuts 29 and 30, washers 31 and 32 being interposed between the nuts and the outer face of the lever 21. It will be seen that when one of the blades is adjusted the other blade will be correspondingly moved
60 through the motion transmitted to it by the connecting lever. The pivot 22 which fulcrums the connecting lever on the front section 5 of the combined clamp and handle is threaded into the said section 5 and it is provided with a reduced smooth por-

tion adjacent to its head to form a journal or pivot for the lever. The smooth portion is formed by reducing the head of the pivot screw and is of greater diameter than the threaded portion of the same.

The handle and clamp 4 is provided with an opening 33 to enable it to be readily gripped and in the operation of the device the combined clamp and handle is placed against the outer edge of the arm of the square as illustrated in Fig. 1 of the drawings. The body portion and the arm of the square are graduated in inches and fractions of an inch and the blades 2 and 3 are graduated into inches and twelfths of an inch, the measuring instrument being de-
70 signed to be used in connection with a chart, not shown, and the scale being preferably one inch to a foot. The adjustment of the combined clamp and handle on the arm 8 of the square will indicate the height of the ridge of the roof and the position of the blades 2 and 3 will give the angle of the inclination or bevel of the common rafters and the hip rafters with relation to the longer arm of the square. In practice, the chart will contain all the necessary data for cutting the various lengths and bevels of the rafters and in practice the size of the parts and the length of the arms of the connecting lever will be properly proportioned to secure an accurate adjustment of the blades 2 and 3 with respect to the square and to each other. The lever is fulcrumed at an intermediate point to form inner and outer arms, and the blades are also pivoted intermediate of their ends, the slots being located at opposite sides of the pivotal points and engaged by the inner and outer arms of the lever so that the blades are caused to move in unison and when one blade is adjusted the other will be automatically adjusted by the operation of the lever. The outer arm of the lever is connected with the outer arm of the blade 3, and the inner arm of the lever is connected with the inner arm of the blade 2, and when one of the blades is lifted the lever will effect a lifting movement of the other blade and a downward movement of either blade will cause the other blade to move in a corresponding direction, so that when one blade makes with the square the angle of the common rafter the other blade will make the corresponding angle of the hip rafter. Also the position and relation of the slot of the blade will also be such as to secure the proper movement of the blades in the adjustment of the instrument. For example, if the run of a common rafter equals 16' and 6" and roof pitch is 8" rise to 12" run and it is required to find the length of the common rafter, the length of the hip rafter and the height of the ridge, the graduate edge of the common rafter blade will be
80 85 90 95 100 105 110 115 120 125 130

placed at 8" on the tongue and 12" on the body of the square. The stock is then moved along the tongue until the common rafter blade crosses the body of the square at 16 $\frac{1}{2}$ ". The reading on the arm of the square will indicate the height of the ridge and the reading of the common and hip rafter blades at the body of the square will give the length of the common and hip 10 rafters.

The combined handle and clamp has its sections formed with arcuate upper edges and the arcuate edge 34 of the front section is beveled and graduated for indicating the angles or inclinations of the blade 15 2. The front and rear sections 5 and 6 are also provided at their inner faces with grooves 35 and 36 for the arcuate ribs of the blades. Various other means may of course be employed for pivotally mounting 20 and clamping the blades in their adjustment but the present construction insures accuracy both in the clamping and the adjustment of the blades.

25 What is claimed is:—

1. An instrument of the class described including a square, a stock adjustable along the arm of the square, a pair of blades extending across the angle of the square at an 30 inclination in the same general direction and pivotally connected at their upper portions with the stock, and a lever pivotally connected with the blades and carried by the stock, said lever being arranged to actuate 35 one of the blades automatically when the other blade is manually adjusted.

2. An instrument of the class described including a square, a stock adjustable on the square, blades mounted for pivotal movement on the stock, one of the blades being provided with a slot on one side of the pivot and the other blade having a slot on the opposite side of the said pivot, and a lever fulcrumed intermediate of its ends on the 45 stock and provided with inner and outer arms operating in the said slots to effect a simultaneous movement of the blades.

3. An instrument of the class described including a square, a combined clamp and handle constituting a stock and composed of 50 inner, outer and intermediate sections, a pair of blades extending in the same general direction across the angle of the square and mounted at their upper portions for pivotal movement between the said sections of the combined clamp and handle, means for adjusting the sections to engage and release the blades, and means for transmitting mo-

tion from one blade to the other, whereby when one of the blades is adjusted manually 60 the other blade will be automatically adjusted.

4. An instrument of the class described including a combined clamp and handle composed of front, rear and intermediate 65 sections, the intermediate section being provided with arcuate ribs and the front and rear sections having corresponding grooves, a pair of blades provided with arcuate grooves stamped in the blades and receiving 70 the ribs of the intermediate section and forming concentric ribs to fit in the grooves of the other sections and means for causing the sections to clamp the blades in their adjustment. 75

5. An instrument of the class described including a combined clamp and handle composed of front, rear and intermediate sections, the intermediate section being provided with arcuate ribs and the front and 80 rear sections having corresponding grooves, a pair of blades provided with arcuate grooves stamped in the blades and receiving the ribs of the intermediate section and forming ribs to fit in the grooves of the other sections, one of the said blades being provided with a slot at one side of the 85 grooves and the other blade being provided with a slot at the opposite side of the grooves, and a connecting lever fulcrumed 90 at an intermediate point on the combined handle and clamp and provided with inner and outer pivots operating in the said slot.

6. An instrument of the class described including a square, a combined handle and clamp having a graduated upper edge and a lower handle portion and movable along the arm of the square, a pair of blades extending in the same general direction across the angle of the square at an inclination and 100 mounted at their upper portions for pivotal movement on the combined handle and clamp, one of the blades being arranged to move over the graduated arcuate portion, means for transmitting motion from one of 105 the blades to the other blade to secure a simultaneous operation of the blades and means for clamping the blades in their adjustment.

In testimony whereof I affix my signature 110 in presence of two witnesses.
